PRIMARY ALCOHOLS FROM THIOCARBOXYLIC ACIDS AND ESTERS

Leopold Ruzicka and Vladimir Prelog, Zurich,
Switzerland, assignors to Ciba Limited, Basle,
Switzerland, a Swiss firm

No Drawing. Application January 28, 1947, Serial No. 724,918. In Switzerland February 6, 1946

12 Claims. (CL 260—297)

1

This invention relates to a process for the production of primary alcohols by treating thiocarboxylic acids containing more than 2 carbon atoms and their derivatives with a finely divided metal charged with hydrogen.

The expression "thiocarboxylic acid" is used herein to denote acids containing the group

or

and as thiocarboxylic acid esters are meant compounds containing the residue

used which contains no water or only small quantities thereof. The reaction generally occurs at room temperature with the evolution of heat. In certain cases however, it is of advantage to heat the reaction mixture in order to accelerate the reaction.

The invention also includes the manufacture of a primary alcohol by starting from a carboxylic acid with the intermediate production of the corresponding thiocompounds. In this manner, for example, palmitic acid can be converted into cetyl alcohol, benzoic acid into benzyl alcohol, pentaacetyl-gluconic acid into pentaacetylsorbitol, 3β-acetoxy-β-ethio-allocholanic acid into 3β-acetoxy-β-ethio-allocholanyl-methanol, and acetyl-oleanolic acid into monoacetylerythrodil. A special advantage of this process is that it can be carried out in a neutral medium under mild conditions, so that sensitive or easily reducible residues present in the molecule remain unchanged. Thus, for example, pyridine carboxylic acids can be reduced to the corresponding hydroxymethyl-pyridines. It is also possible to obtain amino-alcohols from amino-carboxylic acids. When acylamino-carboxylic acids are used there are obtained amino-alcohols in which the amino-group is free or acylated depending on the nature of the acyl residue. Thus, for example, a carbobenzoyl-group is split off during the reduction, whereas this does not occur in the case of a benzoyl group. It has also been found that optically active amino-alcohols can be obtained by the process of the invention from optically active amino-carboxylic acids.

On the other hand, the hitherto known general processes for converting carboxylic acids into primary alcohols, for example, the reduction of the esters with sodium and absolute alcohol or the catalytic hydrogenation of the esters under raised pressure and at high temperature, have the disadvantage that they are not applicable in the case of carboxylic acids which are sensitive to alkalies or are not stable at high temperatures. Thus, for example, the reduction of pyridine carboxylic acids by these known processes leads to piperidine derivatives. Furthermore, the reduction of amino-carboxylic acids to amino-alcohols does not in general proceed smoothly. In particular, it has not been possible hitherto to bring about the reduction of optically active amino-carboxylic acids to amino-alcohols without extensive racemisation.

It is also possible by means of the present process in the case of polycarboxylic acids to convert only certain of the carboxyl groups into the cor-

In the process of the invention a reductive desulphurization takes place with the formation of a primary alcohol. The process is quite generally applicable to aliphatic, alicyclic, aromatic or heterocyclic thiocarboxylic acids containing more than two carbon atoms and esters thereof. The starting materials may also contain substituents, for example, hydrocarbon radicals or substituted or unsubstituted hydroxyl, carboxyl or amino groups. The thiocarboxylic acid group or ester group may be bound to a primary, secondary or tertiary carbon atom. As compared with the free thiocarboxylic acids, the esters, such as the methyl or benzyl esters, have the advantage that they are more stable. The aforesaid starting materials can be obtained easily and in good yield, by the action of the corresponding acid chloride on potassium hydrosulfide or on a mercaptan in the presence of a tertiary amine such as pyridine, triethylamine and the like.

As finely divided metals charged with hydrogen there are used, for example, catalysts such as are obtained by the decomposition of the so-called Raney alloys with solutions of caustic alkalies. Especially suitable is Raney nickel. Alternatively, there may be used other suitable pre-treated metals charged with hydrogen, for example, Raney iron or Raney copper.

The reaction conditions may vary within wide limits. Thus, the reaction may be conducted with Raney nickel in the presence or absence of solvents such, for example, as ether, aliphatic alcohols or dioxane, a solvent being advantageously

3

responding residues containing sulphur, and in this manner to produce hydroxy-carboxylic acids from polycarboxylic acids.

The action of Raney nickel on compounds containing sulphur has been investigated by J. Bougault, E. Cattelain and P. Chabrier [Comptes Rendus de l'Academie des Sciences, vol. 208, page 657 (1939); Bulletin de la Société Chimique de France [51], vol. 6, page 34 (1939), and vol. 7, page 781 (1940); and also by R. Monzingo, D. E. Wolf, S. A. Harris and K. Folkers [Journal of the American Chemical Society, vol. 65, page 1013 (1943)]. Furthermore, the reductive desulphurization by means of Raney nickel has been described by the following authors: V. du Vigneaud and co-workers [Journal of Biological Chemistry, vol. 146, page 475 (1942)]; T. Reichstein and co-workers [Experientia, vol. 1, page 386 (1945)]; N. K. Richtmeyer, C. J. Carr and C. S. Hudson [Journal of the American Chemical Society, vol. 65, page 1477 (1943)]; E. Schwenk and co-workers [Journal of Organic Chemistry, vol. 9, page 1 (1944)]; H. Hauptmann [British Chemical Abstracts, 1945, vol. II, page 245]; and M. L. Wollrom and J. V. Karabinos [Journal of American Chemical Society, vol. 65, page 909 (1944)].

Among these authors only Bougault and co-workers (loc. cit.) treated a thiocarboxylic acid, namely, thioacetic acid with Raney nickel. They observed the formation of acetic acid in aqueous medium and acetaldehyde in absolute alcoholic medium.

From the foregoing literature references it could not be foreseen that that the reductive desulphurization in the case of thiocarboxylic acids and esters thereof would lead to the production of primary alcohols. It is surprising that primary alcohols could be obtained in this manner.

The products of the invention can be used for various purposes depending on their properties or serve as intermediate products.

The invention is described in greater detail in the following examples which are presented by way of illustration and not of limitation. In the examples, the quantities given are parts by weight.

Example 1

1 part of thiopalmitic acid (V. Auger and M. Biltz, Comptes Rendus de l'Académie des Sciences, vol. 136, page 555) is added in small portions to a well stirred suspension of 5 parts of freshly prepared Raney nickel [see Bulletin de la Société Chimique de France [51], vol. 3, page 2330 (1936) and the Journal of the American Chemical Society, vol. 65, page 1015 (1943)] in 100 parts of methanol. After a few hours the mixture is freed from the catalyst by filtration, thoroughly washed, and evaporated to dryness. The residue is dissolved in petroleum ether-benzene (1:1), and adsorbed over aluminium oxide, and elutriated with benzene-ether and ether methanol (1:1), whereby pure cetyl alcohol is obtained which melts at 46-47.5° C. after recrystallisation from acetone.

Example 2

2 parts of thiobenzoic acid (Beilstein, 4th ed., vol. 9, System No. 419) are added to a suspension of 18 parts of Raney nickel in 100 parts of aqueous ethanol of about 95 per cent. strength. The mixture is stirred for a few hours. It is then filtered and the resulting benzyl alcohol melting at 204° C. is recovered from the filtrate. Its phenylurethane melts at 75-76° C.

4

Example 3

5 parts of Raney nickel are added in portions to 1 part of thiopalmitic acid S-methyl ester [A. W. Ralston, E. W. Segebracht and S. T. Bauer, Journal of Organic Chemistry, vol. 4, page 502 (1939)] in 100 parts of boiling aqueous ethanol of about 95 per cent. strength. After working up, cetyl alcohol is obtained in almost quantitative yield. It melts at 46-47.5° C. after recrystallisation from acetone.

Instead of the S-methyl ester, the S-benzyl ester melting at 50-51° C. may be used.

The reaction may also be carried out in dioxane or absolute ether.

Example 4

1 part of thiobenzoic acid S-methyl ester [Obermeyer, Berichte der deutschen chemischen Gesellschaft, vol. 20, page 2922 (1887)] is heated to boiling in 100 parts of ethanol. 5 parts of Raney nickel are then added, and the whole is heated for a short time longer in a reflux apparatus, filtered to remove the catalyst, and the benzyl alcohol is isolated from the filtrate.

Benzyl alcohol is also obtained by carrying out the reaction in aqueous ethanol of about 70 per cent. strength.

Example 5

30 A solution of 1 part of thionicotinic acid S-methyl ester (B. P. 124° C.; obtained from nicotinic acid chloride and methyl mercaptan) in 150 parts of ethanol is boiled in a reflux apparatus for a short time with 5 parts of Raney nickel. The whole is then filtered, thoroughly washed several times with aqueous ethanol, and β -hydroxymethyl-pyridine is isolated from the filtrate by forming the picrate, which melts at 162-163° C.

Example 6

35 3β -acetoxy-*etio*-allothiocholanic acid S-methyl ester (melting at 158-159° C.; obtained from 3β -acetoxy-*etio*-allocholanic acid chloride and methyl mercaptan in presence of pyridine) is treated with Raney nickel in a manner analogous to that described in the foregoing examples. The resulting product is dissolved in benzene and chromatographed over aluminium oxide. There is obtained 3β -acetoxy-*etio*-allocholanyl-methanol, which melts at 141-142° C., in a yield of 93 per cent.

40 By starting from Δ^5 - 3β -acetoxy-*etio*-thiocholanic acid S-methyl ester melting at 183-184° C. there is obtained in a similar manner Δ^5 - 3β -acetoxy-*etio*-cholenyl-(17)-methanol, which forms needles melting at 157-158° C.

Example 7

45 Pentacetyl-sorbitol is obtained in an analogous manner from pentacetyl-thiogluconic acid S-methyl ester (melting at 92-93° C.; obtained from pentacetyl-gluconic acid chloride and methyl mercaptan in presence of pyridine). By subsequent acetylation with acetic anhydride there is obtained hexacetyl-sorbitol melting at 100° C.

Example 8

50 5 parts of acetyl-thioleanic acid S-methyl ester (melting at 167-168° C.; obtained from acetyl-oleanic acid chloride and methyl mercaptan in presence of triethylamine) are treated with 60 parts of Raney nickel in 200 parts of ethanol to yield erythrodiol monoacetate melting at 238.5-239° C. By subsequent acetylation there is obtained from the latter product the known

5

erythrodiol diacetate [Zimmermann, *Helvetica Chimica Acta*, vol. 19, page 247 (1936)].

Example 9

By treating tetradecane-14-carboxylic acid methyl ester-1-thiocarboxylic acid S-methyl ester (melting at 52-53° C.; obtained from thapsic acid methyl ester acid chloride and methyl mercaptan in pyridine) in ethereal solution in an analogous manner, there is obtained by reductive desulphurisation 15-hydroxy-pentadecane-1-carboxylic acid methyl ester melting at 54-55° C.

Example 10

24 parts of benzoylamino-thioacetic acid S-methyl ester (melting at 119.5-121.5° C.; obtained from benzoylaminoacetyl chloride and methyl mercaptan in pyridine) are treated in 400 parts of ethanol with 250 parts of Raney nickel for a short time. The product is then freed from the catalyst by centrifuging, thoroughly washed with ethanol, and the solvent is removed from the filtrate by distillation. A viscous, yellowish oil remains behind, which distils under a high vacuum at a bath temperature of 180° C. 12 parts of the resulting distillate are dissolved in 150 parts of benzene, and boiled with 20 parts of phenyl isocyanate in a reflux apparatus for a short time. The resulting phenyl-urethane of N-benzoylaminoethyl alcohol is separated by filtration, and washed with petroleum ether. It melts at 197° C. after recrystallisation from chloroform-benzene.

Example 11

In a manner analogous to that described in the preceding example an ethereal solution of N-carbobenzoxy-d-thioalanine S-methyl ester (melting at 49-50° C.; obtained by the reaction of the chloride obtained from carbobenzoxy-d-(-)-alanine with methyl mercaptan in pyridine) is treated with Raney nickel. After the reductive desulphurisation the product is freed from the catalyst by filtration, and washed with alcohol. The filtrate is then acidified with hydrochloric acid, and the acid solution is evaporated to dryness. In this manner d-(-)-alaninol hydrochloride is obtained. By allowing the hydrochloride to stand overnight with para-bromobenzoyl chloride in pyridine the O:N-di-para-bromobenzoyl derivative is formed. The latter is purified in benzene solution by chromatography over aluminium oxide, and recrystallisation from benzene-petroleum ether. The product melts at 155° C.

Having thus described the invention what is claimed is:

1. The process of preparing primary alcohols which comprises treating a member selected from the group consisting of thiocarboxylic acids having more than 2 carbon atoms and esters thereof with Raney nickel.

2. The process of preparing primary alcohols which comprises treating a member selected from the group consisting of thiocarboxylic acids having more than 2 carbon atoms and esters thereof with Raney nickel in a neutral organic solvent, and recovering the primary alcohol thus produced.

3. The process of preparing primary alcohols

70

6

which comprises treating a member selected from the group consisting of aminothiocarboxylic acids having more than 2 carbon atoms and esters thereof with Raney nickel.

4. The process of preparing primary alcohols which comprises treating a member selected from the group consisting of acylaminothiocarboxylic acids having more than 2 carbon atoms and esters thereof with Raney nickel.

5. The process of preparing primary alcohols which comprises treating a member selected from the group consisting of optically active acylaminothiocarboxylic acids having more than 2 carbon atoms and esters thereof with Raney nickel.

6. The process of preparing primary alcohols which comprises treating a member selected from the group consisting of aminothiocarboxylic acids having more than 2 carbon atoms and esters thereof with Raney nickel in a neutral solvent, and recovering the primary alcohol thus produced.

7. The process of preparing primary alcohols which comprises treating a member selected from the group consisting of acylaminothiocarboxylic acids having more than 2 carbon atoms and esters thereof with Raney nickel in a neutral organic solvent, and recovering the primary alcohol thus produced.

8. The process of preparing primary alcohols which comprises treating a member selected from the group consisting of optically active acylaminothiocarboxylic acids having more than 2 carbon atoms and esters thereof with Raney nickel in a neutral organic solvent, and recovering the primary alcohol thus produced.

9. The process of preparing primary alcohols which comprises treating a member selected from the group consisting of pyridinethiocarboxylic acids and esters thereof with Raney nickel.

10. The process of preparing primary alcohols which comprises treating a member selected from the group consisting of pyridinethiocarboxylic acids and esters thereof with Raney nickel in a neutral organic solvent, and recovering the primary alcohol thus produced.

11. The process of preparing primary alcohols which comprises treating a member selected from the group consisting of free and esterified thiocarboxylic acids containing an esterified carboxyl group with Raney nickel.

12. The process of preparing primary alcohols which comprises treating a member selected from the group consisting of free and esterified thiocarboxylic acids containing an esterified carboxyl group with Raney nickel in a neutral organic solvent, and recovering the primary alcohol thus produced.
